UNITED STATES PATENT OFFICE.

PATRICK MCGEE, OF PROVIDENCE, RHODE ISLAND.

APPARATUS FOR CLEANING CHARGED GAS-PIPES.

SPECIFICATION forming part of Letters Patent No. 380,910, dated April 10, 1888.

Application filed April 13, 1887. Serial No. 234,565. (No model.)

To all whom it may concern:

Be it known that I, PATRICK MCGEE, of the city and county of Providence, and State of Rhode Island, have invented certain new and useful Improvements in Apparatus for Cleaning Charged Gas-Pipes, of which the following is a full, clear, and exact description, reference being had to the accompanying drawings, forming part of this specification.

10 This invention relates to apparatus for cleaning the bores of the service or distributing pipes of gas-mains.

In the ordinary illuminating-gas distributing systems the gas-main is run underground 15 along a street and parallel to the building-lines of the houses to be supplied with gas. The individual supplies are obtained by running lateral branch or service pipes from the main into the houses.

20 The mains are sometimes constructed so that some provision is made for keeping them from becoming foul and choked up with accumulated deposits. When the branch pipes, which are of a comparatively small bore, become 25 choked or stopped up with deposits, it is a difficult matter to clean the same, and often the pipes are dug up for the purpose of thoroughly cleaning them. Again, it is often attempted to clean the branch pipes by opening 30 the pipe at a point in the cellar of the house between the main and the gas-meter and inserting cleaning or scraping devices in the pipe and loosening the dirt lodged therein, and the loosened dirt is blown out of the pipe 35 by the outflowing gas with which the pipe is charged under pressure. These branch pipes are for the greater part straight, and it is therefore possible to clean them in this manner; but such a method is not at all practical, 40 for the reasons that the escaping gas becomes a dangerous element and is injurious to the workman and contaminates the atmosphere of the house, and, moreover, renders liable the occurrence of an explosion. Besides these objections, the foul deposits removed from the 45 pipe become scattered about the cellar, where they are lodged and remain very offensive for a prolonged period.

The objects of my invention are to provide 50 apparatus for cleaning gas-pipes whereby the cleaning may be effected with perfect safety to

the workman and the surroundings and the work may be done with much thoroughness and cleanliness, and whereby the dirt removed from the pipes may be collected conveniently 55 in a catch-receptacle.

To the above purposes my invention consists in the certain combinations set forth in the claims at the close of this specification, and which comprise the following mechanical features, namely: a charged gas-pipe, a cleaning device and cleaner-rod, a gate-valve adapted to be mounted upon the free end of the gas-pipe, a packing-box for the cleaner-rod to work through, and an injector adapted to be 60 entered within the gas-pipe.

In order that my invention may be fully understood, I have illustrated in the accompanying drawings and will proceed to describe the best form thereof so far devised by me, 70 with the knowledge that the same admits of modifications in details thereof.

In the accompanying drawings, Figure 1 represents a longitudinal sectional view of a portion of a branch service gas-pipe which 75 has attached thereto the gate-valve provided with an attached packing-box. A cleaning device is inserted within the bore of the pipe, and the cleaner-rod extends therefrom through the gate-valve and the packing-box to the 80 outside thereof, so as to be accessible for the necessary manipulation in operating the cleaning device. Fig. 2 represents a sectional view of the gate-valve, taken on line 2 2 in Fig. 1. Fig. 3 represents a view in elevation of another form of cleaning device having a sectional cleaner-rod, which is shown partly broken away. Fig. 4 represents a view 85 in elevation of a tubular injector made in section, and shown partly broken away. 90

In the said drawings like numbers of reference designate corresponding parts throughout.

Referring to the drawings, the number 7 designates the branch or service gas-pipe, 95 which may be supposed to lie within the cellar of a house, and from which a section of pipe has been removed to gain access to the interior of the branch leading to the main. The gas-pipe 7 is of course charged with illuminating-gas, which is maintained under considerable pressure, and hence very efficient 100

sealing means are required to prevent the gas from escaping while the branch is being cleaned.

The gate-valve 8 consists of a casing or coupling, 9, open at both ends, where it is provided with internal screw-threads. In the side of the casing 9 is set a socket-piece, 10, through the central opening of which works the valve-stem 11, which is provided with the hand-wheel 12, keyed to the end of the same. The lower half, 13, of the gate-valve is secured in the bottom of the valve-casing and is provided with a rubber packing, 14, which is formed with a longitudinal semi-cylindrical groove, 15, on its upper face. The upper half, 16, of the valve is secured to the foot of the valve-stem 11, and is likewise provided with a rubber packing, 17, similar to the piece 14. When the upper half of the valve is closed down, on the fixed lower half, as shown in Fig. 1, the grooves of the rubber packings form a tubular channel, and when the said half is raised the opening of the valve is like that shown in Fig. 2.

25 The packing-box 18 is provided with the annular packing 19 at the outer end thereof, while the inner end is formed with a reduced portion, 20, having an external screw-thread designed to fit into the outer mouth of the 30 valve-casing 9, as shown in Fig. 1.

The cleaning device consists of a bar, 21, having two scraper-flanges, 22, running spirally around the same in opposite directions. One end of the bar 21 is screw-threaded to receive the internally-screw-threaded cleaner-rod 23, which forms an even joint therewith.

35 In Fig. 3 the cleaning device is formed differently from that in Fig. 1, and in place of the spiral cleaner-flanges the scraper-head 22 is used, and the same consists of a body having a sharpened circumferential edge and provided with a central perforation, so as to receive the end of the cleaner-rod 23, which is secured thereto by the nut on the screw-threaded end of the rod, as illustrated.

40 In Fig. 4 the injector 24 consists of a tube or pipe having one end closed and provided with the perforation 25, and the cleaner-rod 23 is a pipe which is secured thereto, so that 45 any liquid may be forced therein and out of the injector.

The method of using my improved apparatus will be easily understood. Before removing the section of pipe from the charged branch 50 pipe to gain access to the interior thereof I insert the cleaner-rod 23 or the bar 21, bearing the cleaning device, in the opening of the gate-valve, which I then close tight. Next I remove the section of pipe from the charged 55 branch 7 and quickly insert the cleaning device in the bore of the same and screw the gate-valve upon the opened free end of the pipe, as shown in Fig. 1. This leaves the 60 cleaning device within the pipe, and at the same time the rubber packing of the gate-valve 65 prevents any leakage of gas around the rod or bar. Under this condition the cleaning de-

vice may be readily moved about within the pipe-bore to scrape the walls of the same, but only for a limited distance.

In order to reach a greater distance within the pipe, I attach another section of cleaner-rod 23 to the bar or rod, and in case of the even coupling-joint shown in the drawings the same may be pushed through the closed gate-valve 75 and worked as desired. However, as I intend to use ordinary gas-pipes of small diameter for the sectional cleaner-rods, and as the same are usually coupled up by means of a coupling-sleeve of greater diameter than the pipes, the 80 joint formed will be uneven and cannot be pushed through the closed gate-valve. I therefore have provided a packing-box, 18, before described, and which, after a section of cleaner-rod is coupled on, is introduced over the free 85 end of the same until the uneven coupling-joint is within the box, when the cleaner-rod of uniform diameter is pushed through the closed gate-valve till the packing-box is brought into position to be secured onto the 90 valve-casing 9, as shown in Fig. 1. When this is accomplished, the gate-valve is opened wide, and thereby permits the uneven coupling-joint to pass therethrough and the cleaning device to be introduced farther into the branch pipe 95 toward the main and to clean the bore of the pipe, while the packing 19 of the box securely seals the box against the leakage of gas during the working of the cleaner.

It is to be understood that when a new section of cleaner-rod is to be added and which has an uneven coupling-joint the gate-valve is first closed to prevent escapement of gas, then the packing-box is released and slid back clear off the cleaner-rod while the new section is 105 added, after which the packing-box is replaced, as above described.

The injector may be entered within the branch pipe and the escapement of gas prevented by following the same method and using 110 the same appliances hereinbefore described in the operations of the cleaning device. The injector is used for the purpose of washing the pipes out by the use of a liquid—such, for example, as naphtha.

115 By the use of my invention all the evils resulting from the voluminous escapement of gas and the scattering about the premises of the removed filth of the pipes are completely obviated, and especially is the operator protected against the injury of escaping gas.

Having thus described my invention, I claim as new and desire to secure by Letters Patent—

1. The combination, as hereinbefore set forth, with a gas-pipe, of a cleaning device 125 provided with a rod, a clamping device provided with means whereby it may be fastened upon the opened end of the gas-pipe and support the cleaning-rod within said pipe, and a packing-box mounted upon the outer end of 130 the gate-valve casing, the said cleaning-rod extending through the gate-valve and the packing-box, substantially as and for the purpose herein described.

2. The combination, as hereinbefore set forth, with a gas-pipe, of a cleaning device provided with a sectional rod, a removable gate-valve provided with means whereby it may be fastened to the open end of the pipe and support the cleaning-rod within said pipe, and having the two parts of the valve provided with grooved rubber packing for packing the rod to provide against leakage, and a removable packing-box mounted upon the outer end of the valve-casing for preventing the escape of gas, substantially as described.
